UNITED STATES PATENT OFFICE.

JAMES W. STEVENSON, OF RIVERSIDE, CALIFORNIA.

ORANGE-DRIER.

1,200,775.

Specification of Letters Patent.

Patented Oct. 10, 1916.

Application filed December 13, 1915. Serial No. 66,642.

To all whom it may concern:

Be it known that I, JAMES W. STEVENSON, a citizen of the United States, residing at Riverside, in the county of Riverside and 5 State of California, have invented a new and useful Orange-Drier, of which the following is a specification.

My invention relates to orange driers.

In the orange packing houses it is customary to thoroughly wash the oranges to remove dust and dirt therefrom, and to increase their marketable value and keeping qualities. After the oranges are washed it is necessary to dry them thoroughly, and 15 various devices have been developed for doing this. In many of these devices a blast of air is used to promote evaporation on the surface of the oranges.

The principal object of my invention is 20 to provide an orange drier which will dry the oranges in a superior manner, and which may be operated with the consumption of comparatively little power.

In the previous devices which have been 25 proposed or adopted, the air blast is obtained from a pressure blower or some similar device. It is not necessary that the air which is directed against the oranges be under any considerable pressure, and in my 30 invention I employ a plurality of relatively slowly moving fans, these fans being placed directly above a table across which the oranges are moved. As these fans are of 35 large size, and as they are evenly distributed over the top of the table, it is not necessary that they be driven at a high rate of speed, and in practice they are driven relatively slowly, moving a large volume of air at a low velocity, so that considerable power 40 economies are effected over former types of driers.

Further objects and advantages will be made evident in the following specification.

In the drawings, which are for illustrative 45 purposes only: Figure 1 is a plan view of my device, the hood and a portion of the fans being shown broken away to better illustrate the invention. Fig. 2 is a sectional view taken on a plane represented by the line x^2-x^2 of Fig. 1, this plane being viewed in the direction of the arrows. Fig. 3 is a perspective view of the fan employed. Fig. 4 is an enlarged view of one link and a portion of a roller.

55 In the form of the invention illustrated,

four uprights 11 are provided, these uprights carrying an upper frame 12 to which a hood 13 is secured. The hood 13 can be economically made of canvas, or similar fabric, and consists of a top 14 to which are secured end walls 15 and dividing partitions 16. The hood 13 is open at either side. Carried in bearings 17 on cross members 18 are a plurality of shafts 19 upon each of which is secured a square wooden 60 block 20. Clamped to the block 20 by means of metal strips 21 are a plurality of oil cloth members 22. Secured to one end of each of the shafts 19 are sprockets 23, these sprockets being connected together by chains 24 so 65 that they move together, the first of these shafts being driven from any suitable source of power by means of a sprocket 25 and a chain not shown. Secured to the uprights 11 are tracks 30, and turning in 70 bearings 31 secured to the uprights 11 are shafts 32, these shafts carrying sprockets 33 over which chains 34 pass, certain of the links of the chain having pins 36 formed thereon. Turning freely on the pins 36 are a 75 plurality of rollers 37, these rollers rolling over the upper surface of the tracks 30, and carrying the oranges 40 thereon. The shafts 32 and chains 34 are driven from a source 80 not shown by means of a sprocket 41. 85

The operation of the invention is as follows: Oranges being fed to the rollers 37, and the rollers being driven through the chains 34, sprockets 33, shaft 32, and the sprocket 41, the oranges 40 are carried across 90 the drier being turned over and over in their progress thereacross. The shafts 19 being driven by means of the sprockets and chains 23, 24 and 25, the fabric members 22 are slowly rotated acting as large fans which 95 draw in air at either end, forcing it downwardly against the oranges 40 as they pass thereunder. The end walls and partitions 16 coöperate with the top 14 to force the air from the fans downwardly.

I find in practice that my invention operates with much less power, and occupies much less space, than driers of the old type in which a pressure blower was used to dry the fruit.

100 I claim as my invention:—

1. An orange drier comprising a flexible endless conveyer over which the oranges are carried, a series of shafts parallel with and above said flexible endless conveyer and at 11°

right angles to the line of motion of the oranges, and a series of fans secured to said shafts.

- 5 2. An orange drier comprising a flexible endless conveyer over which the oranges are carried, a series of shafts parallel with and above said flexible endless conveyer and at right angles to the line of motion of the oranges, a series of fans secured to said shafts, and an inclosing hood about said fans for directing the air from said fans against said oranges.
- 10 3. An orange drier comprising a flexible

endless conveyer over which the oranges are carried, a series of shafts parallel with and 15 above said flexible endless conveyer and at right angles to the line of motion of the oranges, a series of flexible blade fans of oil cloth or similar non-hygroscopic material secured to said shafts, and an inclosing hood 20 about said fans for directing the air from said fans against said oranges.

In testimony whereof, I have hereunto set my hand at Riverside, California, this 6th day of Dec., 1915.

JAMES W. STEVENSON.
